UNITED STATES PATENT OFFICE

144,924

DESIGN FOR A COMBINED BOTTLED BEVERAGE COOLER AND NEWSPAPER STAND OR THE LIKE

Alfred F. Immoor, New York, N. Y., assignor to
Pepsi-Cola Company, Long Island City, N. Y.,
a corporation of Delaware

Application August 4, 1945, Serial No. 121,225

Term of patent 14 years

(Cl. D80—9)

To all whom it may concern:

Be it known that I, Alfred F. Immoor, a citizen of the United States, and residing in the Borough of Queens, county of Queens, State of New York, have invented a new, original, and ornamental Design for a Combined Bottled Beverage Cooler and Newspaper Stand or the like, of which the following is a specification, reference being had to the accompanying drawings, forming a part thereof, in which

Fig. 1 is a perspective view, in elevation, of a combined bottled beverage cooler and newspaper stand or the like, showing my new design and with the doors at the bottom open;

Fig. 2 is a similar perspective view of my combined bottled beverage cooler and newspaper stand or the like with the canopy removed from its fittings, for convenience of illustration and with the doors in the bottom closed;

Fig. 3 is a perspective view looking upon one end and upon the rear of my combined cooler and newspaper stand.

I claim:

The ornamental design for a combined bottled beverage cooler and newspaper stand or the like, as shown.

ALFRED F. IMMOOR.
